STOKER AIR CONTROL

Floyd E. Nelson, Rockford, Ill., assignor to Cotta
Transmission Corporation, Rockford, Ill., a
corporation of Illinois

Application January 30, 1939, Serial No. 253,631

8 Claims. (Cl. 236—45)

This application is a continuation in part of my application Serial No. 69,944, filed March 20, 1936.

This invention relates to stokers and has particular reference to a novel means for controlling the volume of air delivered to the retort of an underfeed stoker.

The principal object of my invention is to provide a damper in the air conduit, the position of which changes due to variation of back pressure in the conduit whereby to automatically open the damper wider when resistance to the passage of air through the fuel bed increases, and vice versa.

Another object is to provide an oscillating vane linked to the damper and mounted so as to tend to gravitate to a position corresponding to the fully closed position of the damper and arranged to be raised more and more with increase in back pressure in the conduit to accordingly open the damper wider and wider, whereby to maintain a substantially constant flow of air through the fuel bed regardless of varying bed conditions, arising either from variation in the coal fed to the retort or variation in the amount of clinker allowed to accumulate.

Still another object consists in the provision of an air chamber for the vane, having an adjustable air bleeder valve arranged to be adjusted manually to suit the requirements of a given installation, according to the kind of coal to be burned and the depth of fire bed to be maintained, this valve determining by its adjustment the normal degree of rise of the vane and accordingly the normal or mean condition so far as the amount of damper opening is concerned. A special feature in this connection is the mounting of the oscillating vane in eccentric relation to the arcuate wall of the air chamber so as to have increased clearance for air flow past the vane the farther it moves upwardly and opens the damper more and more, whereby to secure the desired responsiveness and sensitivity and insure against movement of the damper past the point to which it should be adjusted to suit a given condition of the fire bed.

The invention is illustrated in the accompanying drawings, in which—

Figure 1 is a side view of a stoker installation in which the air conduit of the stoker embodies an air control made in accordance with my invention;

Fig. 2 is an enlargement of the air control portion of Figure 1;

Fig. 3 is a longitudinal section through the structure of Fig. 2;

Fig. 4 is a cross-section on the line 4—4 of Fig. 3;

Fig. 5 is a side view of another air control generally similar to that shown in Fig. 2;

Fig. 6 is a longitudinal section through the structure of Fig. 5;

Fig. 7 is a cross-section on the line 7—7 of Fig. 6, and

Fig. 8 is a sectional detail on the line 8—8 of Fig. 7.

Similar reference numerals are applied to corresponding parts throughout the views.

The stoker appearing in Figure 1 has the conventional hopper 5 to store the coal which is fed through a conduit 6 into the bottom of the retort 7. The coal fed to the retort rises therein to maintain a desired depth of fire bed, the coal being fed from the hopper through the conduit 20 by a screw in the usual way. The screw is driven through reduction gearing in the housing 8 by an electric motor indicated in dotted lines at 9, the same being disposed behind the blower housing 10. Simultaneously with the feeding 25 of coal to the retort, air is discharged tangentially from housing 10 through the downwardly inclined neck 11 into the air conduit 12 and conducted into the retort 7, whereby to supply sufficient air to the fire bed for good combustion. In the past, various types of air controls have been provided, some involving merely a manually adjustable damper or shutter and others involving dampers or shutters intended to be adjusted automatically to suit conditions. 30 Most of the automatic controls with which I am familiar have been rather complicated and expensive, and, on the whole, not very reliable. Then too, most of them if adapted to meet one condition, would not take care of others apt to arise in service, with the result that they have not given satisfaction. The air control of my invention is one which is simple and inexpensive, and, when once manually adjusted to suit the requirements of a given installation, automatically adjusts itself thereafter to varying bed conditions, to the end that the stoker is kept 35 operating efficiently at all times.

According to my invention, a damper 13 is mounted on a horizontal shaft 14 in the neck 11 for oscillatory movement. The screws 15—16 have conical seats receiving the conical ends of the shaft 14 with a free working fit to insure smooth and easy turning of the damper. A pointer 17 is fixed to the shaft 14 outside the 40 45 50 55

neck 11 and moves relative to a graduated indicator plate 18 to indicate the degree of opening of the damper. This pointer points to "0" when the damper is closed and to "5" when the damper is fully opened. An arm 19 on the damper 13 has a link 20 attached thereto connecting the damper with the actuating vane 21. The vane is designed to work by air pressure, as a piston or diaphragm, except that its movement is oscillatory. It is mounted on a horizontal shaft 22 received with a free working fit in bearings 23 in the opposite sides of a segmental housing 24 carried on top of the neck 11 adjacent the bend therein. The vane 21 has a certain amount of clearance between the edges thereof and the side and end walls of the housing, as clearly appears in Figs. 3 and 4, so that while this vane will be deflected upwardly under air pressure from beneath, air will pass around the edges of the vane 21 and escape from the housing through the slot 25 more or less freely depending upon the adjustment of a bleeder valve 26. The latter may be of any suitable or preferred type and, in this case, is in the form of a round rod received with a close working fit in the elongated bearing 27 provided on the top wall of the housing. One side of the rod has a flat milled thereon, as indicated at 28, so that as the rod is turned, more or less of the slot 25 is opened to the atmosphere through another elongated slot 29 in the wall of the bearing 27. The rod 28 has a pointer 30 on the enlarged end thereof, which moves relative to graduations 31 on the side wall of the housing 24 to indicate the position of the valve. The housing 24 will preferably be cast in one piece, as a die casting, for economy and to insure the desired accuracy of fit of the vane 21 therein. This housing is shown as fastened by means of screws 32 to the wall of the neck 11 over the opening 33 therein, and a gasket 34 interposed between the parts makes for an air-tight connection. The vane 21, owing to the position of the housing tends to gravitate to the lowermost position in which it is shown in Fig. 3, and, while it takes very little air pressure upon the vane to cause it to start rising, it is manifest that more and more pressure is required to raise the vane the nearer it approaches a horizontal position. Now, the vane will reach substantially a horizontal position when the damper 13 is substantially fully opened and pointer 17 points to "5." I may provide an arm 35 on one end of the shaft 22 adjustably secured by means of a set screw 36, to permit placing it at any desired angle relative to the vane, and having a plurality of spaced holes 37 into any one of which a screw 38 may be entered to fasten a counterweight or weights 39 closer to or farther from the axis of oscillation of said vane. In this way, any desired operating characteristics so far as the operation of the vane 21 is concerned may be obtained, and more or less air pressure will be required to bring the vane to a certain position.

In operation, whenever the usual room thermostat stops the stoker because the heat demand has been satisfied, the vane 21 gravitates to the position shown in Fig. 3 and closes the damper 13, thus leaving the fire bed dependent upon the small amount of air that will seep past the damper 13, and what air will find its way through openings in and around the fire door of the furnace. The fact that the damper is closed makes for economy because the coal will naturally burn slower under those conditions, and it also makes for better comfort by avoiding overheating.

When the temperature drops sufficiently for the thermostat to start the stoker again, the incoming air from the blower housing 10 gradually raises the vane 21 and opens the damper 13 and, depending upon the adjustment of the valve 26, the damper 13 will assume a certain position of partial opening, where it is in equilibrium, with the pointer 17 at one of the numbered positions between 0 and 5, or at some position between two numbers. The setting of the valve 26 is made to suit the requirements of the installation, according to the kind of coal to be burned and the depth of fire bed to be maintained. The thing that determines the position of the damper 13 is the back pressure in conduit 12, which acts on the vane 21, and, obviously, if the air valve 26 is adjusted so that air passing around the edges of this vane is allowed to escape freely, so that a greater pressure differential exists between the opposite sides of the vane, the vane will rise higher and accordingly open the damper 13 wider. Now, assuming that the valve 26 has been set so that under normal conditions the damper 13 will open to an extent where the pointer 17 is opposite say the numeral 2, and, due to, let us say, an influx of finer coal than usual, the resistance to air flow through the fire bed is increased: this will result in raising the vane 21 a trifle higher and accordingly the damper 13 will be opened wider to admit more air to meet the demand. In other words, the control meters the volume of air required for a certain fuel bed. In that way, good combustion is secured. By the same token, if more than the usual amount of clinker is left on the fire bed and the resistance to air flow through the fire bed is accordingly increased, the damper 13 will be opened wider automatically to take care of the need for increased volume of air. This air control, in other words, compensates automatically for varying fuel bed conditions and thereby insures keeping the stoker operating efficiently at all times. It is manifest that the air control involves so few parts and these are of such simple and durable construction that there is very little likelihood of the mechanism getting out of order and requiring attention. A few simple instructions will enable the user to make whatever adjustments may be desirable. Usually, the valve 26 when once properly set according to instructions will not require any readjustment unless the user changes to some other kind of coal or decides upon maintaining a different depth of fire bed.

While I have disclosed a damper 13 in the air conduit operated by the vane 21 to meter the volume of air delivered to the retort 7, it should be evident that the same results could be obtained by leaving the vane 21 where it is and substituting for the damper a shutter on the air intake 40 on the blower housing 10 to meter the intake of air to the blower. Obviously, the volume of air delivered to the retort would be varied in the same way by such a shutter operated in response to movement of the vane 21. The claims should be construed accordingly, the word "damper" used therein being considered in its broad sense as referring to any air control or metering member, such as a shutter.

Referring now to Figs. 5 to 8, in which the numeral 11a designates the end of the air discharge neck on the blower housing and 12a designates the adjacent end portion of the air conduit through which air is delivered to the fire bed, this air control, like the other, involves an oscil-

lating vane 21a operatively connected with a damper 13a through the medium of a link 28a. The vane 21a, like the vane 21, is arranged to be operated by air pressure to communicate movement to the damper, the segmental housing 24a in which the vane operates being in communication with the air conduit through the opening 33a so as to subject the vane to whatever static pressure exists in the air conduit. As in the air control first described, a slot 25a permits escape of air from that space in the housing behind the vane, and air will pass around the edges of the vane and out through the slot more or less freely depending upon the adjustment of the bleeder valve 26a, which, in the present instance, is in the form of a flat strip of sheet metal pivoted on a screw 40 at one end for oscillatory adjustment relative to the slot 25a and arranged to be held in adjusted position by means of a set screw 41 threaded in the cover plate 42 mounted on the housing 24a and arranged to be locked by means of a lock nut 43. The end of the valve 26a projects through a slot 44 in one end of the cover plate 42 to permit manual adjustment thereof when the set screw 41 is loosened and obviously the position of the valve in relation to the slot is a sufficient indication of the adjustment, because when the valve is in a mid-position in the slot, as shown in Fig. 8, the slot 25a is half covered. The vane 21a in the present structure is counterbalanced by a weight 45 fixed by means of a set screw 46 in the proper position of endwise adjustment relative to an L-shaped arm 47 carried on the pointer 17a fixed to the shaft 14 carrying the damper 13a. The portion of the arm 47 carrying the weight 45 is parallel to the pointer 17a, and hence when the weight is adjusted along the arm, its radius with relation to the shaft 14 is changed and its counterbalancing value is increased or decreased. In the clockwise movement of the vane 21a, the counterweight 45 is moved in a counterclockwise direction through a corresponding angularity and therefore exerts a greater and greater counterbalancing effect the farther the vane is raised. Now, it is important to note that the center 22a about which the vane 21a oscillates is slightly eccentric relative to the arcuate inside wall 48 of the housing 24a. This is indicated in Fig. 6 by the fact that the dot-and-dash arc *a*—*b* described by the outer end of the vane in its movement is in closer spaced relation to the arc 48 at *a* than at *b*. In actual practice, the housing 24a is preferably die cast with the bearing holes 49 for the shaft 22a eccentric just a few thousandths of an inch, so that the clearance between the outer end 50 of the vane 21a and the arcuate wall 48, at *b*, is just a few thousandths of an inch greater than at *a*. This varying clearance has proved to be very important in securing the desired responsiveness and sensitiveness and for insuring accurate movement of the damper and preventing movement past a certain point to which the damper should be adjusted to suit a given condition of the bed. I have found that this varying clearance is directly responsible for the stopping of the vane 21a at a certain position when there is a change in the fire bed, due to a sudden influx of "fines", for example, or, due to an accumulation of ashes or clinkers, and a wider opening of the damper is required and is produced automatically. I have found that if a greater variation in clearance is provided between points *a* and *b*, a different sized counter-

weight is required or a different position of adjustment thereof. This indicates that there is a relationship between the vane's clearance and the counterbalancing force of the weight, and it is clear, therefore, that what happens when the fire bed develops resistance to air flow through it and requires a wider opening of the damper is this: The increase in back pressure in the air conduit 12a acting on the vane 21a, which up to that time was in a balanced position of equilibrium, causes the vane to move in a clockwise direction, opening the damper wider, the vane moving upwardly to a point where, due to the greater clearance between the vane and the wall 48, there is a sufficiently increased flow of air possible past the vane and out through the slot 25a to establish a new position of equilibrium with the counterweight 45 also exerting a greater counterbalancing effect by reason of its shift in position with the damper. Actual experience shows that when the vane has moved to a certain point and adjusted the damper accordingly, it will not be balanced in any other position one way or the other from that position. For example, if one moves the pointer 17a one way or the other from the self-assumed position, it will invariably come back to exactly that position, thus showing clearly that the parts are unbalanced in any other position and therefore return to the previous self-assumed balanced position.

It is believed the foregoing description conveys a good understanding of the objects and advantages of my invention. The appended claims have been drawn with a view to covering all legitimate modifications and adaptations.

I claim:

1. A stoker air control comprising a damper mounted within an air conduit for delivering air under pressure to a stoker retort, said damper having oscillatory movement from a position closing the opening therethrough to another position substantially opening said conduit, a segmental-shaped housing communicating with said conduit adjacent the damper, a gravitating vane mounted for oscillatory movement in said housing and operatively connected with said damper so as to close the damper when the vane is in lowermost position, said vane being operable with a predetermined clearance in said housing to permit air flow from the conduit into the housing and past said vane, whereby said vane is adapted to be raised by increased pressure in said conduit to open said damper and lowered upon a decrease in pressure to close said damper, the vane and housing being formed and disposed relative to one another so as to increase the size of the air passage between the vane and housing as the vane moves in a direction to open the damper, and adjustable means for permitting discharge of air to the atmosphere from said housing from behind the vane therein.
2. A stoker air control comprising a damper mounted within an air conduit for delivering air under pressure to a stoker retort, said damper having oscillatory movement from a position closing the opening therethrough to another position substantially opening said conduit, a segmental-shaped housing communicating with said conduit adjacent the damper, a gravitating vane mounted for oscillatory movement in said housing and operatively connected with said damper so as to close the damper when the vane is in lowermost position, said vane being operable with a predetermined clearance in said housing to permit air flow from the conduit into the housing

and past said vane, whereby said vane is adapted to be raised by increased pressure in said conduit to open said damper and lowered upon a decrease in pressure to close said damper, the vane and housing being formed and disposed relative to one another so as to increase the size of the air passage between the vane and housing as the vane moves in a direction to open the damper, a counterweight carried on an arm arranged to oscillate with one of the aforesaid oscillatory damper and vane, and adjustable means for permitting discharge of air to the atmosphere from said housing from behind the vane therein.

3. A stoker air control comprising a damper mounted within an air conduit for delivering air under pressure to a stoker retort, said damper having oscillatory movement from a position closing the opening therethrough to another position substantially opening said conduit, a segmental-shaped housing communicating with said conduit adjacent the damper, a gravitating vane mounted for oscillatory movement in said housing on an axis eccentric with respect to the arcuate wall of said housing and operatively connected with said damper so as to close the damper when the vane is in lowermost position, said vane being operable with a predetermined clearance in said housing variable due to the eccentric mounting of the vane to permit air flow from the conduit into the housing and past said vane, whereby said vane is adapted to be raised by increased pressure in said conduit to open said damper and lowered upon a decrease in pressure to close said damper, the clearance between the vane and housing increasing as the vane moves in a direction to open the damper, a counterweight on an arm oscillating with one of the aforesaid damper and vane so as to give increased counterbalancing effect with increased opening of the damper, and adjustable means for permitting discharge of air to the atmosphere from said housing from behind the vane therein.

4. A stoker air control comprising a damper mounted within an air conduit for delivering air under pressure to a stoker retort, said damper having oscillatory movement from a position closing the opening therethrough to another position substantially opening said conduit, a segmental-shaped housing communicating with said conduit adjacent the damper, a gravitating vane mounted for oscillatory movement in said housing on an axis eccentric with respect to the arcuate wall of said housing and operatively connected with said damper so as to close the damper when the vane is in lowermost position, said vane being operable with a predetermined clearance in said housing variable due to the eccentric mounting of the vane to permit air flow from the conduit into the housing and past said vane, whereby said vane is adapted to be raised by increased pressure in said conduit to open said damper and lowered upon a decrease in pressure to close said damper, the clearance between the vane and housing increasing as the vane moves in a direction to open the damper, and adjustable means for permitting discharge of air to the atmosphere from said housing from behind the vane therein.

5. A draft regulator comprising a damper mounted within a conduit for oscillatory movement from a position closing the opening therethrough to another position substantially opening said conduit, a segmental-shaped housing

communicating with said conduit adjacent the damper, a vane mounted for oscillatory movement in said housing and operatively connected with said damper, said vane being movable with a predetermined clearance in said housing so as to permit air flow through the housing past said vane, the vane and housing being formed and disposed relative to one another so as to increase the size of the air passage between the vane and housing as the vane moves in a direction to open the damper, and adjustable means on the housing for regulating the flow of air past the vane.

6. A draft regulator comprising a damper mounted within a conduit for oscillatory movement from a position closing the opening therethrough to another position substantially opening said conduit, a segmental-shaped housing communicating with said conduit adjacent the damper, a vane mounted for oscillatory movement in said housing and operatively connected with said damper, said vane being movable with a predetermined clearance in said housing so as to permit air flow through the housing past said vane, the vane and housing being formed and disposed relative to one another so as to increase the size of the air passage between the vane and housing as the vane moves in a direction to open the damper, a counterweight carried on an arm arranged to oscillate with one of the aforesaid oscillatory damper and vane, and adjustable means on the housing for regulating the flow of air past the vane.

7. A draft regulator comprising a damper mounted within a conduit for oscillatory movement from a position closing the opening therethrough to another position substantially opening said conduit, a segmental-shaped housing communicating with said conduit adjacent the damper, a vane mounted for oscillatory movement in said housing on an axis eccentric with respect to the arcuate wall thereof and operatively connected with said damper, said vane being movable with a predetermined clearance in said housing so as to permit air flow through the housing past said vane, the clearance between the vane and housing increasing as the vane moves in a direction to open the damper, and adjustable means on the housing for regulating the flow of air past the vane.

8. A draft regulator comprising a damper mounted within a conduit for oscillatory movement from a position closing the opening therethrough to another position substantially opening said conduit, a segmental-shaped housing communicating with said conduit adjacent the damper, a vane mounted for oscillatory movement in said housing on an axis eccentric with respect to the arcuate wall thereof and operatively connected with said damper, said vane being movable with a predetermined clearance in said housing so as to permit air flow through the housing past said vane, the clearance between the vane and housing increasing as the vane moves in a direction to open the damper, a counterweight on an arm oscillating with one of the aforesaid damper and vane so as to give increased counterbalancing effect with increased opening of the damper, and adjustable means on the housing for regulating the flow of air past the vane.

FLOYD R. NELSON.
